UNITED STATES PATENT OFFICE.

LEE S. CHADWICK, OF CLEVELAND, OHIO, ASSIGNOR TO THE CLEVELAND METAL PRODUCTS COMPANY, OF CLEVELAND, OHIO, A CORPORATION OF OHIO

REFRIGERATOR.

1,281,909.

Specification of Letters Patent. Patented Oct. 15, 1918.

Application filed February 28, 1913. Serial No. 751,214.

To all whom it may concern:

Be it known that I, LEE S. CHADWICK, a citizen of the United States, residing at Cleveland, in the county of Cuyahoga and State of Ohio, have invented a certain new and useful Improvement in Refrigerators, of which the following is a full, clear, and exact description, reference being had to the accompanying drawings.

10 This invention relates to refrigerators or ice boxes, and particularly to refrigerators of the type and size commonly used in homes for the preservation of perishable food stuffs, although a number of features of my 15 invention are equally well adapted for use in connection with refrigerators of the larger and stationary type. It is important, in devices of this character, that there be no cracks, crevices, or corners present in which 20 matter may accumulate and, if permitted to remain, result in the generation of impurities and germs. The principal feature of my 25 invention is to provide a construction of a refrigerator or ice-box whereby the following objects are attained: sanitation, effective isolation, and economy of time in and ease of assembling, and cleaning. Furthermore, 30 my invention provides a refrigerator which is neat and attractive in appearance, of substantial construction and cheap of production.

Generally speaking, my invention may be defined as consisting of the various combinations of elements set forth in the claims 35 annexed hereto and illustrated in the accompanying drawings forming a part hereof wherein Figure 1 is a perspective of the refrigerator of my invention; Fig. 2 is a similar view, the front of the refrigerator being 40 open; Fig. 3 is a vertical sectional view of the refrigerator. Figs. 4 and 5 are a central vertical section and a front elevation, respectively, of a latch for the front of the refrigerator, certain parts of Fig. 4 being 45 shown in elevation; Fig. 6 shows in perspective the members of a separable hinge used in connection with the removable portion 50 of the front of my refrigerator; Fig. 7 is a vertical sectional detail of a portion 55 of the drain and trap; and Fig. 8 is an elevation of my refrigerator, showing a modified form of front therefor.

Similar reference characters are used to

designate corresponding parts throughout the several views of the drawing.

The refrigerator comprises generally a cabinet A which is supported upon the legs B and which is provided with the doors C, D, and E. The door C is supported by the hinges e from the front edge of one of the side walls of the cabinet and swings against one side of the jamb F. In like manner the doors D and E are supported by hinges d and e, respectively, which are secured to the front edge of the opposite side wall of the cabinet, and swing against the opposite side of the jamb F. Between the doors D and E there is a horizontal sill G, having one of its ends secured rigidly to the jamb F, and the other end swung from the forward edge of the side wall of the cabinet by means of a hinge H, which I prefer to make separable, one of such hinges being shown in detail in Fig. 6. The sill G and the jamb F comprise a T-shaped frame which is hinged to the cabinet A in the manner just mentioned and locked in place by the latches I which connect the upper and lower ends of the jamb to the front edges of the top and bottom walls respectively of the cabinet.

The doors C, D, and E may be locked to the jamb F by means of any approved form of latch, one form of such latch being shown for the various doors and indicated, respectively at c', d' and e'.

The latch I, shown in detail in Figs. 4 and 5, comprises a swinging arm which terminates at one of its ends in a handle i and which is pivoted upon a stud i' projecting from and riveted to a plate i''. This plate is secured to the front edge of the cabinet wall by suitable screws i''. A spring-pressed plunger i' occupies a recess i''' formed in the rear surface of the end of the arm opposite the handle i. This plunger is adapted to register with depressions i'' formed in the face of the plate i'' and hold the arm in either its locked or unlocked position and, when intermediate of the depressions i'', the plunger rides upon the surface of the plate. A latch plate i'' is secured to the adjacent end of the jamb F and is provided with a projecting portion i'' adapted to occupy a recess i''' in the rear face of the arm i. The edge of the recess farthest removed from the fulcrum of the arm, is substantially concentric

therewith, but the coöperating edge of the projection i^8 is somewhat spiral with respect to the fulcrum of the arm and forms a cam whereby the jamb is drawn toward the wall 5 when the arm is swung into locked position. It will be noticed, from Fig. 4, that these edges are inclined and interlock when in engagement. A camming or wedging action is also accomplished by the engagement of the 10 front of the projection i^8 , which is inclined from near its center toward one end thereof, and the adjacent straight wall of the notch i^9 . The action of the cam thus provided is at right angles to the action of the previously described cam, and jointly they effect 15 a very secure binding and locking of the parts together. A correct positioning of the parts is assured by the coöperation of the overhanging edge of the latch plate i^7 with 20 the notch i^{10} formed in the adjacent edge of the plate i^2 . A lug i^{11} projects rearwardly from the handle i to near the surface of the jamb F , and prevents the operation of the latch I , when the doors of the refrigerator 25 are closed, by its engagement with the projecting edges of the doors. In this manner the latches I are locked at the same time that the latches c' , d' and e' are in locked condition.

30 The hinge H , heretofore referred to, comprises the member h which is secured by screws to the end of the sill G , and the member h' which is secured in a like manner to the front edge of the side wall of the cabinet. The member h is provided with a substantially cylindrical extension h^2 from which depends a hinge pintle h^3 adapted to be received by the socket provided by the hook h^4 projecting from the end of the member h' .

From the construction thus far described it will be seen that I provide a refrigerator, the entire front of which may be opened as shown in Fig. 2 in the following manner: 45 By releasing the latch c' the door C may be swung upon its hinges to open position, and this will permit the latches I to be operated and unlock the jamb F from the front edges of the top and bottom walls of the 50 cabinet. Thereafter, the entire section comprising the jamb F , the sill G , and the doors D and E , may be swung upon the hinges d , e , and H , it being understood that the pintles of all of these hinges are in axial 55 alignment.

Supported from the rear of the T-shaped frame which is formed by the jamb F and the sill G , is the ice receptacle J . This ice receptacle comprises a drip pan j which is 60 rectangular in plan and which is surrounded by a vertical flange j' . The front portion of the flange j' is fastened to the sill G and said flange has secured to its side and rear portions the side and rear walls j^2 and j^3 , respectively, of the ice receptacle. These

walls are preferably formed from a single piece of corrugated metal, as shown most clearly in Fig. 2. A brace j^4 , which is secured to the jamb F , is provided for that side wall j^2 which is farthest removed from the jamb, to strengthen said wall and maintain it in proper position. The forward edge of the opposite side wall j^2 is secured to the rear of the jamb F by nails or screws which pass through the flange j^5 extending 70 inwardly from the front edge of said wall. A small angle bar j^6 has one of its flanges fastened to the upper edge of this wall, for a purpose which will be mentioned hereinafter. The bottom of the drip pan j is inclined from the bottom edge of the vertical flange j' toward the drain opening j^7 , which is located at the transverse center of the rear portion of said bottom. An opening j^8 occupies the central portion of the bottom of the ice receptacle and is surrounded by an upwardly projecting flange. The ice is supported upon a removable metal platform j^{10} a slight distance above the bottom 85 of the ice receptacle. 90

A drain pipe K is secured to the bottom of the drip pan j by rivets which pass through the flange k of the pipe and through that portion of the bottom of the pan surrounding the drain opening j^7 . Screwed 95 upon the lower end of the pipe K is a shell k' which has its front cut away, for cleaning purposes. The lower edge of the shell k' is substantially semi-circular in outline and is adapted to rest upon the upper edge 100 of the cup l of the trap L , and a segmental flange l' , which projects upwardly from the top of the cup l , embraces the lower edge of the shell k' . Projecting from the side of the cup l opposite the flange l' is a fin l^2 which 105 has an upwardly incline face. Threaded within a boss which projects upwardly from the bottom of the cup l , is the end of a nipple l^3 . This nipple extends through the bottom wall of the cabinet A and receives a nut l^4 on its lower threaded end by which the cup l is securely clamped in place through the intervention of the nipple l^3 , washers l^5 being interposed between the faces of the cup and nut and the adjacent 110 surfaces of the cabinet wall. The trap is completed by a cap l^6 which rests upon the bottom of the cup l and which is provided with notches l^7 about its lower edge through which the water from the drain may pass. 115 The tops of these notches are below the top of the nipple l^3 whereby the drain is water-sealed against the admission of air. 120

It will be seen upon referring to Figs. 2 and 3, that the drain pipe K and the shell k' form an effective support or leg for the rear of the ice receptacle J , when the refrigerator is closed. In the closing of that part of the front which supports the ice receptacle, the lower rear edge of the shell k' rides upon the 125 130

inclined upper face of the fin l^2 which projects from the trap cup l and elevates slightly the rear of the ice receptacle to its normal position, from which position it drops slightly when the refrigerator is open, through the resiliency of the metal from which it is constructed.

A plate M , which has its upper edge turned over and under the horizontal flange 10 of the angle bar j^6 and is supported thereby, hangs down alongside the ice receptacle J to within a short distance of the bottom of the cabinet A' (see Fig. 3). This plate and the inner surface of the opposed cabinet side 15 wall are provided with horizontal ribs m and 42, respectively, for the support of the ends of removable shelves N . The shelves N space the plate M from said wall when the refrigerator is closed, thereby retaining the 20 plate in position. When it is desired to clean the refrigerator, the door C may be opened, the shelves N withdrawn, the jamb F unlatched, and the front of the cabinet opened in the manner previously described 25 (see Fig. 2). The plate M may then be swung outwardly from the bottom of the ice receptacle and the space between the plate and the wall of the receptacle thoroughly cleaned, or, if desired, the plate may 30 be removed altogether by simply swinging it out a sufficient distance to permit its upper edge to be disengaged from the angle bar j^6 , and unhooking of the parts being necessary since lateral shifting of the plate M 35 upon the angle bar is prevented by the downturned rear end of the horizontal flange of the angle bar. To expedite a more thorough cleaning and sunning of the parts of the refrigerator, the doors D and E may be 40 unlatched from the jamb F , and the jamb F , sill G , and ice receptacle removed by disconnecting the hinge H .

The interior of the cabinet A is provided with a metallic shell or liner 40, which is 45 preferably enameled.

Ribs 42 are pressed outwardly from that side wall of the shell which is farthest removed from the ice receptacle (see Fig. 3) and these ribs are located opposite the ribs 50 m on the plate M and support the ends of the shelves N opposite those supported upon the ribs m . It will be noticed also that the corners of the shell or liner are made rounding to further the feature of sanitation.

While I prefer to construct the front of my refrigerator as shown particularly in Figs. 1 and 2, I wish it to be understood that, without departing from the spirit of my invention, I may employ in place of the T -shaped frame which consists of the jamb F and sill G , a rectangular frame Q , such as shown in Fig. 8, to which the doors D and E may be hinged and from the rear side of which the ice receptacle may be supported, 60 the frame Q being swung from the front

edge of the side wall of the cabinet A by separable hinges H and adapted to be locked in closed position by the latches I . Furthermore, if it should be found desirable, I may hinge the frame Q at the top or bottom and apply the locks I at the opposite end and side thereof, and, although I have shown in my drawings, a refrigerator having three doors, I do not wish to confine myself to this as any desired number of doors may be 75 employed.

Having thus described my invention, what I claim is:

1. In a device of the character set forth, the combination with a cabinet having an 80 open side, of a T -shaped frame which is arranged to occupy a portion of the open side of the cabinet, that member of the frame which corresponds to the cross of the T having its opposed ends detachably connected to the opposite edges of the open side of the cabinet, and the end of the member which corresponds to the stem of the T having its end removably hinged to another edge of said open side, a door that is hinged 85 to the edge of the cabinet opposite the last mentioned edge and having a portion for coöperation with the first mentioned member of the T -shaped frame, and doors hinged to that edge of the cabinet to which the 90 frame is hinged, the hinges of the last mentioned doors and the hinges of the frame being in axial alinement, said last mentioned doors having portions which engage 95 portions of both members of the T -shaped 100 frame.

2. In a device of the character set forth, the combination with a cabinet having an open side, of a T -shaped frame which is arranged to occupy a portion of the open side 105 of the cabinet, that member of the frame which corresponds to the cross of the T having its opposed ends detachably connected to the opposite edges of the open side of the cabinet, and the member which corresponds to the stem of the T having its end removably hinged to another edge of said open side, a door that is hinged to the edge of the cabinet opposite the last mentioned edge and having a portion for coöperation with the 110 first mentioned member of the T -shaped frame, doors hinged to that edge of the cabinet to which the frame is hinged, the hinges of the last mentioned doors and the hinge of the frame being in axial alinement, 115 said last mentioned doors having portions which engage portions of both members of the T -shaped frame, and latches for securing the edges of the doors to adjacent portions of the frame.

3. In a device of the character set forth, the combination with a cabinet having an open side, of a frame hinged to the open side 120 of the cabinet, a receptacle carried by the frame, and a member within the cabinet 125

1 having an inclined portion that is arranged to be traversed by a part of the receptacle while the frame is being swung to normal position, thereby to elevate said receptacle 5 to normal position should the same have sagged below such position.

4. In a device of the character set forth, the combination of a cabinet having an opening, a jamb extending from top to bottom thereof, a door pivoted to the cabinet at one side of said jamb and having an edge overhanging the same, a member extending laterally from the jamb, means pivotally supporting the same from the cabinet, a door 15 pivoted to the cabinet at the opposite side of the jamb from the first mentioned door and having an edge overhanging the jamb, and a latch for the jamb interposed between the overhanging edges of the doors, the operation of said latch being prevented by one 20 of the doors when said door is closed.

5. In a device of the character set forth, the combination of a cabinet having an opening, a jamb extending there cross, doors on opposite sides of said jamb, means pivotally supporting the jamb from the cabinet, and a latch for said jamb arranged so as to be blocked by one of said doors when said door is closed.

30 6. In a refrigerator, the combination of a cabinet, a closure therefor, a metallic lining for the cabinet having shelf seats projecting from one of its side walls, a receptacle supported within one side of the cabinet, a plate swingably connected to the upper end of said receptacle so that the same may be 35 swung outward therefrom, said plate having shelf seats and being opposed to the aforesaid wall of the liner, and shelves supported

by the seats of the wall and plate and acting to hold said plate against the side of the receptacle.

7. In a refrigerator, the combination of a cabinet, a closure therefor, a metallic liner for said cabinet, one wall whereof is provided with a shelf seat, a receptacle within the cabinet, a plate the upper edge whereof interlocks with the upper edge of one of the side walls of the receptacle in such manner as to require said plate to be swung away from said wall before the same may be disengaged from the upper edge thereof, said plate having a shelf seat and being opposed to the aforesaid wall of the liner, and a shelf that is adapted to rest upon said shelf seats and retain the plate in normal position.

8. In a refrigerator, the combination of a cabinet, a closure for one side thereof, a receptacle removably supported within the cabinet, a plate the upper edge whereof interlocks with the corresponding edge of one of the side walls of the receptacle in such manner as to require said plate to be swung away from said wall before the same may be disengaged from the upper edge thereof, said plate having a shelf seat, a liner for the cabinet having a wall that is opposed to the aforesaid plate, said wall being provided with a shelf seat, and a shelf that is adapted to rest upon said seats and retain the plate in normal position.

In testimony whereof, I hereunto affix my signature in the presence of two witnesses.

LEE S. CHADWICK.
